Patented Aug. 19, 1975

236,324

COMBINED CAN OPENER AND KNIFE SHARPENER

Carl E. Richard, Enfield, and Gerald E. Rideout, South
Windsor, Conn., assignors to General Signal Corpora-
tion

Filed Aug. 27, 1973, Ser. No. 392,150

Term of patent 14 years

Int. Cl. D7—99

U.S. Cl. D8—35

FIG. 2

FIG. 1

FIG. 4

FIG. 3

FIG. 6

FIG. 5

FIG. 1 is a front elevational view of a combined can opener and knife sharpener showing our new design; FIG. 2 is a right side view of the can opener.

FIG. 3 is a top plan view thereof.

FIG. 4 is a left side view of the can opener.

FIG. 5 is a rear view of the can opener.

FIG. 6 is a bottom plan view thereof.

We claim:

The ornamental design for a combined can opener and knife sharpener as shown.
